UNITED STATES PATENT OFFICE.

MICHAEL ADOLF GULBRANDSEN, OF NEW YORK, N. Y., ASSIGNOR OF ONE-HALF TO
MARTIN J. LUND, OF BROOKLYN, NEW YORK.

CLOSURE FOR COMBINED LIFE-RAFTS AND STEAMER-TRUNKS.

1,295,737.

Specification of Letters Patent. Patented Feb. 25, 1919.

Application filed June 26, 1917. Serial No. 177,111.

To all whom it may concern:

Be it known that I, MICHAEL A. GULBRANDSEN, a citizen of the United States, residing at New York city, in the county of 5 New York and State of New York, have invented new and useful Improvements in Closures for Combined Life-Rafts and Steamer-Trunks, of which the following is a specification.

10 This invention is an improved closure for a combined life raft and steamer trunk adapted for use ordinarily as a steamer trunk and also adapted for use in an emergency as a life raft, the object of the invention being 15 to provide an improved device of this character which is simple in construction, is light and readily portable, and which while ordinarily used as a steamer trunk can in a case of emergency be readily arranged for use as 20 a life raft.

The invention consists in the construction, combination, and arrangement of devices hereinafter described and claimed.

In the accompanying drawings:—

25 Figure 1 is an elevation of a combined steamer trunk and life raft embodying my invention, showing the collapsible floats folded.

Fig. 2 is an end elevation of the same with 30 the floats inflated.

Fig. 3 is a plan of the same.

Fig. 4 is a detailed sectional view of the trunk.

Fig. 5 is a similar view of the same.

35 Fig. 6 is a similar view showing the compressed air tank.

Fig. 7 is a detailed view, showing a portion of the trunk in elevation and showing one of the inflatable bags in section.

40 In the preferred embodiment of my invention I provide a trunk 1 which comprises a top 2, a bottom, side walls 3 and end walls 4. The top is provided with an oblong rectangular opening of suitable dimensions and

45 with the improved closure 4 for said opening. The closure is hinged at one side as at 5.

In furtherance of my present invention, the walls of the trunk are provided at points around the opening with inwardly extending inclined strips 6 which are secured at their lower edges as at 7 to the inner surfaces of the trunk walls and the upper edges of which provide flanges 8 and are rounded as shown and are covered with sealing liners 50 as of rubber or other suitable material and

which engage in correspondingly shaped grooves 10 in the lower side of the closure and hence serve to hermetically seal the closure and thereby prevent leakage and render the trunk water tight. Wedge-shaped blocks 60 11 are secured in the angles between the strips 6 and the walls of the trunk. Bolts 12 pass through the strips, blocks and sidewalls and are provided at their outer ends with eyes 12 through which straps 13 pass, the 65 straps being adapted to be fastened around the trunk and to extend across the bottom and top thereof.

Adjacent to its free side and its ends the closure is provided with cylindrical thimbles 70 14 which are counter-sunk therein and have outwardly extending flanges 15 at their upper ends and are secured in place by screws 16 the heads of which fit in openings in said flanges. The blocks 11 are provided, at 75 points below and which register with the thimbles with nuts 17 which are counter-sunk in said blocks and have flanges 18 secured on said blocks by screws 19. Securing screws 20 are swivelly connected to and pass 80 through openings in the bottoms of the thimbles and are also vertically movable in the thimbles and have heads 21 arranged in the thimbles and each provided with a pivotally connected thumb hold 22 to enable 85 the screws to be manually turned. These screws may be engaged with the nuts to firmly secure the closure in closed position and hermetically seal the same.

The trunk is provided near one end with 90 a suitable number of compartments 23 for the reception of food, water and other supplies and one of which compartments also contains an air pump 24. Each compartment is provided in the top with a hermetically sealed screw cap 25 which may be 95 manually turned and hence opened or closed. The air pump is provided with a suitable hose.

The compartments 23 are arranged in a 100 tank 23^a in which compressed air is stored, and which can be readily supplied with compressed air by means of the air pump or any other suitable means. The said compressed air tank has a nipple 23^b to which 105 the hose may be directly connected.

On opposite sides of the trunk are 110 inflatable bags 26 which are made of suitable material and which when inflated with air form floats to add to the buoyancy of the

trunk and to enable the trunk when thrown over-board to be employed as a life raft. These floats or air bags are laced or otherwise suitably secured as at 27 to the straps 5 13 at points near the top and bottom of the trunk and when deflated and folded are secured in folded position, against the sides of the trunk by suitable straps 28.

The closure 4 is shown provided in the 10 upper side with a recess 29 for the reception of a suitable air or other suitable kind of cushion 30.

The air pump is used for inflating the 15 pneumatic floats, the latter being provided with suitable valves 31 to which the tube or 20 hose of the air pump may be attached.

The pneumatic floats may be directly inflated from the compressed air storage tank 23^a, by means of the hose if desired.

While I have herein shown and described 25 a preferred form of my invention, I would have it understood that changes may be made in the form, proportion and construction of the several parts without departing 30 from the spirit of my invention and within 35 the scope of the appended claim.

I would have it understood, however, that

my novel closure is especially adapted for use in the trunk shown and described because of its capacity of excluding water.

Having thus described my invention, I claim:—

In a closure, the combination of a trunk body open at its upper side, inclined strips fixed to the inner sides of the upright walls 35 of the body and projecting above the plane of the upper edges of said walls, blocks interposed between said strips and the body walls, nuts fixed in the said blocks, a cover hinged to the body and having grooves in 40 its underside arranged to receive and break joints with the upper edges of said strips, packing interposed between the upper edges of the strips and the walls of the grooves, thimbles counter-sunk in the upper side of 45 the cover, and threaded screws journaled in the bottom walls of the thimbles and adapted to register with and enter and engage the nuts in the interposed blocks of the body; the said screws having handles disposed in 50 the thimbles.

In testimony whereof I affix my signature.

MICHAEL ADOLF GULBRANDSEN.
